UNITED STATES PATENT OFFICE.

GEORGE ALVIN BECK, OF QUINCY, ILLINOIS.

DESIGN FOR A GRAVE-MARKER.

48,743.

Specification for Design.

Patented Mar. 21, 1916.

Application filed January 28, 1916. Serial No. 74,891. Term of patent 7 years.

To all whom it may concern:

Be it known that I, GEORGE A. BECK, a citizen of the United States, residing at Quincy, in the county of Adams and State of Illinois, have invented a new, original, and ornamental Design for Grave-Markers, of which the following is a specification, reference being had to the accompanying drawing, forming part thereof.

The figure is a perspective view of the grave marker, showing my new design.

I claim:

The ornamental design for a grave marker, as shown.

GEORGE ALVIN BECK.

Witnesses:

CARL E. EPLER,
ROSE VOSSE.
